UNITED STATES PATENT OFFICE

149,619

DESIGN FOR A FOLDING TRAY TABLE

Hubert J. Dahm, Los Angeles, Calif.

Application September 28, 1946, Serial No. 133,641

Term of patent 14 years

(Cl. D33—14)

To all whom it may concern:

Be it known that I, Hubert J. Dahm, a citizen of the United States of America, residing in the city of Los Angeles, in the county of Los Angeles, State of California, have invented a new, original, and ornamental Design for a Folding Tray Table, of which the following is a specification, reference being had to the accompanying drawings, forming a part thereof.

Figure 1 is a view in perspective of the under side of a folding tray table in folded position, embodying my new design;

Figure 2 is a view similar to Figure 1 but with the legs in a mid-position as during the setting-up operation;

Figure 3 is a view similar to Figures 1 and 2 with the legs entirely extended into supporting position;

Figure 4 is a view in perspective from the side, showing the table in its normal position;

Figure 5 is a side elevational view; and

Figure 6 is an end elevational view thereof.

I claim:

The ornamental design for a folding tray table, substantially as shown and described.

HUBERT J. DAHM.
